SOLENOID CONSTRUCTION

Benjamin Norton Foster, Keene, N. H., assignor
of one-half to Kingsbury Machine Tool Corporation,
Keene, N. H., a corporation of New Hampshire

Application August 24, 1934, Serial No. 741,341

9 Claims. (CL 175—338)

The present invention is an improvement in the construction of solenoids which are especially adapted for employment with alternating current.

5 One of the features of the present invention is the provision of a simply and cheaply constructed article which avoids excessive losses by eddy currents.

Another feature of the invention is the provision of a solenoid having an internal expansion spring which is protected by the solenoid structure from eddy current effects therein.

10 A further feature of the invention is the provision of a solenoid having a closely fitting and externally smooth housing of heat conductive nature which permits readily the dissipation of heat developed within the solenoid.

15 Still another feature of the present invention is the provision of a solenoid having a minimum of constructive parts, each of which is simply and cheaply manufactured and assembled.

20 Still another feature of the present invention is the provision of a solenoid in which the "pull curve" may be modified without extensive change or adjustment of the structure involved.

25 Still another feature of the present invention is the provision of a solenoid in which the parts are made of materials and of shapes which assure a minimum of wear and a long life for the structure.

With these and other features as objects in view, an illustrative form of practicing the invention is shown on the accompanying drawing, in which:

30 Figure 1 is a diametrical sectional view.

Figures 2 and 3 are transverse sectional views substantially on lines 2—2 and 3—3 of Figure 1.

Figure 4 is an end elevation.

35 Figures 5 and 6 are side elevations of one end piece.

Figure 7 is a side elevation of another end piece.

Figure 8 is a sectional view substantially on line 8—8 of Figure 7.

40 Figure 9 is a view corresponding to Figure 1, but showing an assemblage of parts for attaining a different "pull curve".

In the drawing, the structure is enclosed in an outer housing 10 of metal having a smooth external surface which is illustrated as cylindrical. A reduced portion 11 connects the portion of major diameter with a neck portion 12 of lesser diameter. The open end of the larger portion 10 is provided with internal screw threads to receive a closing and securing plug 13. This plug has a cavity on its inner face which

5 closely engages the external surface of and aligns a winding sleeve 14 which itself has a shoulder 15 leading to an enlarged portion 16 which is tightly received within the cavity of the portion 12 of the outer casing.

A thin coil head or end member 17 (Figures 1, 5 and 6) has three radial pins 18 which extend into apertures of the winding sleeve 14. A second head or end member 19 (Figures 1, 7 and 8) similarly has three pins 20 which extend into the winding sleeve 14. These pins therefore serve in the preliminary assembly of the winding sleeve and the end members preparatory to the winding of a coil 21 therein. It will be noted that this preliminary assembly is mechanically 15 rigid and that the winding of the coil may occur on a lathe or normal type of winding machine and that this coil may be impregnated and baked in the usual way if so desired.

20 A movable core or armature member has a slotted head end 25 with an aperture 26 by which it may be connected as usual to a link which is to be actuated thereby. This armature is slidable in and closely fits the internal surface of the winding sleeve 14 which as illustrated is 25 cylindrical and concentric with the outer casing. A central axial hole 27 is provided in the armature for receiving an expansion spring 28. Further, the armature is slotted longitudinally at a number of places as shown in Figure 2 to provide kerfs 29 which serve to interrupt electrical circuit paths for eddy currents. One of these kerfs 29a extends to the hole 27 so that there is provided no complete circuit for eddy current, while the other kerfs 29 are illustrated as terminating short of this hole and operate to restrict 30 localized eddy currents within the mass of the armature.

35 A pole piece or stop member 30 which similarly is provided with kerfs 29, 29a (Figure 3) has 40 a cavity 31 for receiving the other end of the expansion spring 28 and has a threaded aperture which is engaged by a screw 32 which extends through the closing plug 13 and serves to hold the pole piece 30 fixedly in position and in supporting relation to the sleeve 14.

45 It is preferred to cut away the abutting edges of the armature and pole piece (Figure 1) to provide recesses 33 which receive any oil or dirt which may be scraped from the internal wall of 50 the winding sleeve 14, and thus permit the armature to come into abutting relation with the stop member or pole piece 30.

55 In assembly, when the parts have been prepared and winding has been assembled upon the

winding sleeve 14 as stated above, with the ends of the winding extending through holes 19b, 19c of the end member 19 and connected to terminal blocks 35 which are secured to the end 19 within 5 peripheral kerfs or notches 19n thereof, the insulated connecting leads 36, 37 are brought through apertures 19a of the end member 19 and attached likewise to the blocks 35; the other ends of the leads 36, 37 are guided through the 10 casing 10 and out through the apertures 10x thereof. The winding sleeve 14 is now slid into position with its enlarged end 16 closely received by the reduced end 12 of the casing 10 until the end member 19 engages fixedly with a casing as 15 a stop to limit the further inward movement of these parts. A pin 19p of member 19 enters the slot 10a of the casing 10 (Figure 4) and prevents relative rotation of the sleeve and its winding with respect to the casing, so as to avoid shearing 20 of the leads 36, 37. The spring 28 is inserted in the stop member 30. The plug 13 is then screwed into position until it engages and supports the winding sleeve and holds the assembly of the winding sleeve and its winding tightly in 25 position in the casing 10; this operation is performed by a suitable wrench engaged in holes 13b. The screw 32 is then inserted and/or tightened and the plug operates thereafter to complete the interrupted magnetic shield and to hold the 30 associated parts rigidly and tightly in position.

In order to assure a minimum of wear of the parts, the armature 25 and preferably also the stop member 30 and winding sleeve 14 are coated at least at their engaging faces with chromium. 35 This material has been found advantageous, as a very thin layer of it provides excellent security against excessive wear and yet does not modify the magnetic properties of the parts, as might be the case if case-hardening or like treatment other 40 than treatment for optimum magnetic effects were given to these members.

In order to reduce losses by eddy currents, the winding sleeve 14 and also the outer casing 10 and plug 13 preferably have corresponding slots 45 14a, 10a, 13a as shown, as this prevents a direct and simple circuit for flow of eddy currents in a direction parallel or concentric with the turns of the winding itself.

The proportion of the total length which is utilized for the pole piece and for the armature will 50 vary according to the demand for a particular type of "pull curve". Thus, as the pull falls off very rapidly as the armature or plunger moves away from the pole piece, and naturally this pull 55 is very high at the position of abutment of the parts, it is possible by changing the relative lengths of pole pieces and armatures, as illustrated in Figures 1 and 9, to produce a marked hump in the pull curve at substantially any point desired. 60 With the form shown in Figure 1, the hump occurs substantially at half-stroke. The sub-division of the solid armature, by providing the radial kerfs, changes the total amount of iron in the magnetic circuit and the character of the hump 65 may be modified by changing the size and number of such kerfs.

In construction, the armature and pole piece 70 are of course made of iron or steel alloys with a hard chromium plating placed thereon after appropriate heat treatment for obtaining optimum magnetic properties. The winding sleeve is preferably of phosphor bronze or like non-magnetic substance and its end members are of insulating 75 material. The casing and end plug are prefer-

ably made of a material suitable for forming a magnetic shield of high heat conductivity.

In operation, the device performs excellently on alternating current as no circuits are provided for the movement of eddy currents, all of the parts being slotted to avoid such flow. In particular, it is found that the structure of the armature and pole piece of solid material, with slots formed therein, is not only advantageous mechanically as providing an easy manner of assemblage 10 (in preference to laminations) but also it permits the use of an internal expansion spring 28 for separating the parts upon deenergization of the winding. This spring, however, is protected by the magnetic shield formed by the surrounding 15 armature and pole piece when the parts are in abutment, which is the normal condition during energization of the coil. Therefore, no such flow of eddy currents occurs in the spring such as to weaken or modify its elastic property. 20

Owing to the smooth external shape of the casing 10 and its closing plug 30, the solenoid may be located and maintained in a cavity of substantially the same size in the frame of a mechanism which is to be controlled thereby. Thus, it 25 may be inserted in a housing H (Figure 1) in close contact therewith so that the heat generated by electrical losses in the coil are transmitted to the casing 10 and thus to the housing H. Likewise, any heat produced by eddy currents in the 30 casing 10 is likewise transmitted. It will be noted that the walls of kerfs 29 in the armature and pole piece similarly operate as radiation surfaces and the movement of the armature causes a pump-like action to ventilate and cool these 35 parts. Hence it is found in practice that the solenoid has a great efficiency as it operates at high current and magnetic intensities without excessive heat losses and with a rapid transfer of such heat as is generated. 40

It is obvious that the invention is not limited solely to the form of construction shown, but that it may be modified in many ways within the scope of the appended claims.

Having thus fully described my invention, what 45 I claim as new and desire to secure by Letters Patent, is:—

1. A solenoid structure especially for alternating currents comprising a hollow metal casing having a longitudinal slot, a metal winding sleeve 50 having a longitudinal slot, a winding on said sleeve, a closing plug for said casing and having a radial slot, and an armature movable in said sleeve, said slots operating to interrupt the paths of eddy currents. 55

2. A solenoid structure comprising a hollow casing having an end aperture, a winding sleeve supported in said aperture, and a closing plug for said casing having a shoulder for supporting said sleeve at a point remote from said aperture. 60

3. A solenoid structure especially for alternating currents, comprising a hollow casing having a reduced end, a winding sleeve supported in said reduced end, end members secured on said sleeve, a winding on said sleeve having its terminals 65 extending through the reduced end, and a closing plug for said casing engaging said sleeve, one of said end members cooperating with said reduced end in positioning said sleeve in said casing.

4. A solenoid structure especially for alternating currents, comprising a hollow casing, a winding sleeve in said casing and a winding thereon, an armature slidably in said sleeve and comprising a block of magnetizable metal having a plurality of longitudinal kerfs therein, one of said 75

kerfs completing an air gap from the axis of the armature to its periphery to prevent the circuit of eddy currents therearound.

5. A solenoid structure especially for alternating currents, comprising a sleeve having a winding thereon, an armature member having a plurality of longitudinal kerfs and an axial cavity extending from its inner end, a stop member having an axial cavity aligned with said first cavity, and an extension spring located in said cavities and protected by said armature and stop members when said members are in abutting relation.

10. 6. A solenoid structure comprising a sleeve having a winding thereon, an armature member and a stop member each having an axial cavity, an extension spring located in said cavities and protected by said members when they are in abutting relation, the lengths of the said members being constructed and arranged to provide a hump on 15 the the "pull curve" at a predetermined point, said members having longitudinal external kerfs thereon for interrupting eddy currents and for distributing the magnetizable metal to give said hump a predetermined characteristic.

20. 7. A solenoid structure comprising a sleeve having a winding thereon, and an armature member having a case of magnetizable material of selected

magnetic properties, said case being coated with chromium to protect the same against wear and deterioration without influencing the magnetic properties thereof.

25. 8. A solenoid structure comprising a sleeve having a winding thereon, a stop member and an armature member closely fitting in and guided by said sleeve, said members having longitudinal external kerfs therein, the edges of the members being cut away between the kerfs for permitting 10 the members to come into abutting relation regardless of material scraped from the sleeve at said edges.

15. 9. A solenoid structure especially for alternating currents, comprising a sleeve having a winding thereon, an armature member having an axial cavity extending from its inner end, a stop member cooperative with said armature member, and an extension spring having an end in said cavity and guided by said armature member, said spring 20 being protected by said armature and stop members when said members are in abutting relation, said armature member having a longitudinal air gap extending from its cavity to its outer surface to interrupt the path of eddy currents. 25
